(57) **CLAIM**

The ornamental design for a pick-up cartridge, as shown and described.

DESCRIPTION

FIG. 1 is a front view of a pick-up cartridge;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a perspective view thereof;

FIG. 8 is a front view showing a state of separation thereof; and,

FIG. 9 is a perspective view showing the state of separation thereof, showing our design.

The design shown is not to be limited to any particular size and may be scaled larger or smaller.
